CONTROL MECHANISM FOR PRESSING MACHINES

Joseph P. Daly, New York, N. Y., assignor to The American Laundry Machinery Company, Cincinnati, Ohio, a corporation of Ohio

Application March 4, 1935, Serial No. 9,193

17 Claims. (Cl. 121—38)

This invention relates to improvements in control mechanism for pressing machines.

In pressing machines of the type which have coacting pressing members of the bed or platen 5 type which are brought together for a pressing operation and held in that position for a period of time, one of the problems in control mechanisms concerns itself with the protection of the operator against injury while the pressing members are moving toward each other to close the press.

My control mechanism provides in a press of this type improved control means arranged to keep both hands of the operator occupied during 15 the closing of the press.

My invention also includes improved operating mechanism for closing a pressing machine and causing a pressing or ironing operation between coacting pressing members, together with improved control mechanism for maintaining the 20 press closed under fluid pressure.

Other improved features of my press control mechanism include specially arranged devices for insuring the safe operation of the machine under 25 various working conditions, all as will more clearly appear in the accompanying specification and drawings, and the essential features of which will be summarized in the claims.

Fig. 1 of the drawings shows an end elevation 30 of a pressing machine with the press operating mechanism and control devices shown in section and somewhat diagrammatically to enable their operation to be more easily understood; while Figs. 2 and 3 are views of the power and control 35 mechanism of Fig. 1 showing the parts in different operated positions.

My improved press operating and control mechanism is applicable to many types of presses but I have chosen to illustrate the same in conjunction 40 with a well-known type of pressing machine, such as is used in laundry and garment work. The machine illustrated comprises a pair of coacting relatively movable pressing members 10 and 11, one or both of which may be made 45 movable for the purpose of closing and opening the press. In the present instance I have illustrated the member 10 as providing a stationary bed secured on a frame 12 and the member 11 is a coacting pressing chest or head carried by a 50 head lever 13 which is pivotally mounted at 14 on the frame. For opening and closing the press I have provided a pair of toggle links 15 pivotally connected together at the knuckle 16 and mounted 55 between pivot 17 located on the frame and pivot 18 mounted on the rear end of the head lever

so that with the parts as shown in Fig. 1, the pressing members are in their open position and with the parts moved to the broken line position of Fig. 1, the press is closed for an ironing operation. The press is biased toward and normally held in open position as shown in full lines in Fig. 1 by a spring 19 secured between the rear end of the head lever on the one hand and the frame of the machine on the other.

Power means is provided for relatively moving 10 the pressing members from open to closed position and the particular means illustrated comprises two cylinder and piston motors having suitable motion transmitting mechanism connected therewith for relatively moving the pressing members 15 to closed position. These motors are so arranged that neither of them alone has sufficient power stroke to completely close the press but both of them must act together. I do not desire to be limited in the arrangement of these motors other 20 than as defined in the appended claims when construed in view of the prior art.

I have illustrated as one embodiment of my invention two axially aligned cylinder and piston motors 20 and 21 which preferably have a common cylinder head 22 between them. The construction shown comprises a single member which provides the cylinder walls for both motors and has a partition wall integral therewith which forms the common cylinder head between the two 30 motors. The motor 20 thus comprises a cylinder 23 in which reciprocates a piston 24 whose piston rod 25 is pivotally mounted at 26 on a bracket connected with the frame. The motor 21 comprises a cylinder 27 housing a piston 28 whose piston rod 29 is suitably connected to the toggles 15, the connection shown being at the knuckles 16. Suitable passages are provided for the ingress and egress of fluid to and from the motors and in the form illustrated the inlet passages 30 40 and 31, one for each motor, and the exhaust passage 32 for motor 20 are formed integral in the common cylinder head or partition wall 22. Also each motor is provided with an open exhaust port 33 and 34 to relieve the pressure on the idle face 45 of the piston. Each of the motor cylinder walls is also provided with a port 35 and 36 which is uncovered by the piston as it reaches the end of its power stroke. The purpose of these ports will be later disclosed.

The means for supplying motive fluid to the motors 20 and 21 includes a combined flow and exhaust conduit 37, 38 suitably connected with the passages 30 and 31 through a shuttle valve mechanism 39, 40 to be later described and communi- 55

cating with valve casings 41, 42 located at the front of the machine in which are housed valves operable by manuals 43 and 44 which are spaced apart so as to require the use of both hands of the operator to actuate them. The arrangements of the valves in casings 41 and 42 are exactly alike so that one only will be described. In valve casing 41 is housed a normally closed inlet valve 41a and a normally open outlet valve 41b which are mounted on a common stem 41c for actuation by manual 43. Spring 41d biases the valves toward the normal position. The supply of motive fluid is by way of conduit 45 which has branches 46 and 47 leading to casings 41 and 42 respectively.

Means is provided for supplying to each of the motors 20 and 21 motive fluid independent of the manually controlled supply for holding the press closed under fluid pressure. In the present instance each motor upon a predetermined relative travel between its piston and cylinder operates to establish this independent motive fluid supply for the other motor. In the form shown, valve casings 48 and 49 are rigidly mounted on the cylinder structure and each casing is provided with a normally closed inlet valve and a normally open outlet valve, the construction of which is similar to that described in connection with valve casings 41 and 42 and the valves have been given analogous subscripts. The valve stems 48c and 49c are actuated by cam portions 25' and 29' on the respective piston rod as the pistons approach the end of their power stroke as will be later described. A conduit 50 establishes communication between the inlet and outlet valves in casing 48 and the port 36 in the cylinder wall of motor 21. In the same manner conduit 51 establishes communication between the inlet and outlet valves in casing 49 and the port 35 in the cylinder wall of motor 20. Conduits 45a and 45b provide a supply of motive fluid for the casings 48 and 49 respectively.

The shuttle valve construction shown at 39 and 40 comprises a cylinder or other suitable valve body in which a valve member such as the disk 39a or 40a reciprocates in a manner to establish communication between the inlet passages 30 and 31, for the introduction of fluid into the motor cylinders, and the manually controlled conduits 37 and 38; or alternatively communicating with the conduits 50 and 51 which latter connection is made possible by the conduits 52 and 53 which establish communication between conduit 51 and casing 39 on the one hand and between conduit 50 and casing 40 on the other hand. The valve disks 39a and 40a are preferably biased to the position shown in Fig. 1 by springs 39b and 40b.

For opening the press I have provided exhaust conduit 54 which establishes communication between passageway 32 and valve casing 55 also preferably located at the front of the machine. This casing houses a normally closed outlet valve 55a biased in closed direction by a spring 55b. A stem 55c is actuated by a manual 56 to open the outlet valve.

With the parts in the full line position of Fig. 1, the operator arranges the lay of the work upon the member 10 and actuates the manuals 43 and 44. Motive fluid then flows from conduits 45 and 46 through valve 41a and conduit 37 to valve casing 39 where the pressure acting against valve 39a moves the disk to the right as seen in the drawings, whereupon the fluid passes through passageway 30 to the working face of piston 24 which moves the cylinders 23 and 27 and likewise piston

28 rearwardly or to the left as shown in Fig. 1. The effect of this movement is to partially close the head 11 upon the bed 10. At the same time, fluid flows from conduits 45 and 47 through valve 42a and conduit 38 to valve casing 40 moving shuttle valve 40a to the left as seen in Fig. 1 which permits fluid to continue through passageway 31 to the working face of piston 28. This piston then moves relatively to its cylinder 27 and this additional stroke is sufficient to completely close the press. This simultaneous action of both of the motors 20 and 21 moves the toggle links and the pressing head to the broken line position of Fig. 1 and moves the pistons 24 and 28 relatively to their respective cylinders to the position of Fig. 3. In this position of the pistons, each of them has passed the ports 35 and 36 respectively in the cylinder walls and at substantially the same time cam portions 25' and 29' on the respective piston rods have engaged the valve stems 48c and 49c respectively which are arranged to lie in the path of the traveling cams. The action of cam 25' is to close valve 48b and to open valve 48a which admits motive fluid from conduit 45a to conduit 50 and through port 36 to cylinder 27 against the working face of piston 28 in the position which it then occupies. The action of cam 29' is exactly similar in its effect upon the valves in casing 49 and establishes a flow of motive fluid from conduit 45b through conduit 51 and port 35 to the working face of piston 24. This establishes maintaining pressure against the faces of the two pistons which is independent of the manually controlled supply used to preliminarily close the press and therefore the manuals 43 and 44 may be released and the press will remain closed.

To open the press the operator actuates manual 56 which moves valve 55a to its open position and permits the exhaust of fluid from motor 20 through passageway 32 and conduit 54. The press will then open under the influence of spring 19 which first moves piston 24 relative to cylinder 23 causing cam 25' to move away from valve stem 48c which permits spring 48d to close valve 48a and open valve 48b. Pressure is then exhausted from motor 21 through conduit 50 and outlet valve 48b which permits spring 19 to return the press to its full open position. In the arrangement shown, with the press fully closed, the toggle links 15 must stop short of fully straightened position if spring 19 is to be effective for opening the press. However, those skilled in the art will understand that the toggles might be moved to fully straightened position in which case the spring 19 would be arranged to pull one or both of the toggles toward the broken position which would be the full equivalent of the arrangement shown.

The function of the shuttle valves in casings 39 and 40 is to insure the return of the press to fully opened position should the operator actuate manual 43 or 44 and then release one or the other of said manuals without completing the normal cycle above described. If the valves 39a and 40a were mere check valves this pressure introduced by small amounts into cylinders 23 and 27 would be trapped in these cylinders with the result that the press would remain partly closed. With the arrangement shown, if the operator actuates one of the manuals, say 43 in Fig. 2, shuttle valve 39a is temporarily moved toward the right and piston 24 starts on a power stroke or rather cylinder 23 moves relative to piston 24. If the manual 43 is then released pressure is relieved against the rear face of valve 39a and spring 39b will move the valve to the full line position shown

in Fig. 1 and cylinder 23 will be opened to exhaust through passageway 30, casing 39, conduits 52 and 51, port 35, cylinder 23 and port 33 to the atmosphere or alternatively from conduits 52 and 51 to casing 49 and outlet valve 49b to the atmosphere. Analogous circuits are possible for the other motor and will not be described.

With the arrangement shown it will be obvious that maintaining pressure for piston 24 in its position corresponding to a completely closed press will also be provided through conduit 52, casing 39 and passageway 30. A similar maintaining effect at motor 21 is also established.

I have thus provided operating and control mechanism for a pressing machine which requires that both hands of the operator remain upon spaced safety manuals until the press is fully closed. If either of the manuals is released before such a condition is reached the press will open to the extent that it may be controlled by the released manual and in any case if one manual is operated and the other is released the press will not close to a dangerous position and air will be continuously exhausted until the press is properly operated. The circuits described for maintaining the pressure in the two motor cylinders can only become effective after both motors have been actuated to move the press parts to a safe closed position. Thereafter the press will remain fully closed until the release manual is actuated.

What I claim is:

1. In a pressing machine, a pair of coacting relatively movable pressing members, two cylinder and piston motors and motion transmitting mechanism connected therewith for relatively moving said members to completely close the press, the stroke of either of said motors alone being insufficient to completely close the press, means for supplying motive fluid to said motors including two manuals, one for each motor and spaced to require two hand operation, and means actuated by each of said motors upon predetermined relative travel between its piston and cylinder for establishing a supply of motive fluid for the other of said motors independent of its manually controlled supply.

2. In a pressing machine, a frame, a stationary pressing member thereon, a coacting pressing member movable toward and from said stationary member, two axially aligned fluid motors each having cylinder and piston elements, one element of each motor being connected with the frame and the movable pressing member respectively, the other elements of said motors being rigidly connected together, the working strokes of both motors being necessary to completely close the press, means for supplying motive fluid to said motors including two manuals, one for each motor and spaced to require two hand operation, and means actuated by each of said motors upon predetermined relative travel between its piston and cylinder for establishing a supply of motive fluid for the other of said motors independent of its manually controlled supply.

3. In a pressing machine, a pair of coacting relatively movable pressing members, two cylinder and piston motors and motion transmitting mechanism connected therewith for relatively moving said members to completely close the press, the stroke of either of said motors alone being insufficient to completely close the press, means for supplying motive fluid to each of said motors including a normally closed inlet valve and a normally open outlet valve and a manual

for actuating said valves to open the inlet and close the outlet valve, said manuals being spaced to require two hand operation, and means actuated by each of said motors upon predetermined relative travel between its piston and cylinder for establishing a supply of motive fluid for the other of said motors independent of its manually controlled supply.

4. In a pressing machine, a frame, a stationary pressing member thereon, a coacting pressing member movable toward and from said stationary member, two axially aligned fluid motors each having cylinder and piston elements, one element of each motor being connected with the frame and the movable pressing member respectively, the other elements of said motors being rigidly connected together, the working strokes of both motors being necessary to completely close the press, means for supplying motive fluid to each of said motors including a normally closed inlet valve and a normally open outlet valve and a manual for actuating said valves to open the inlet and close the outlet valve, said manuals being spaced to require two hand operation, and means actuated by each of said motors upon predetermined relative travel between its piston and cylinder for establishing a supply of motive fluid for the other of said motors independent of its manually controlled supply.

5. In a pressing machine, a pair of coacting relatively movable pressing members, two cylinder and piston motors and motion transmitting mechanism connected therewith for relatively moving said members to completely close the press, the stroke of either of said motors alone being insufficient to completely close the press, a port in the wall of each cylinder adapted to be uncovered by the associated piston near the end of its power stroke, means for supplying motive fluid to said motors including two manuals, one for each motor and spaced to require two hand operation, and means actuated by each of said motors upon predetermined relative travel between its piston and cylinder for establishing communication between a motive fluid supply and the port in the cylinder wall of the other motor.

6. In a pressing machine, a frame, a stationary pressing member thereon, a coacting pressing member movable toward and from said stationary member, two axially aligned fluid motors each having cylinder and piston elements, one element of each motor being connected with the frame and the movable pressing member respectively, the other elements of said motors being rigidly connected together, the working strokes of both motors being necessary to completely close the press, a port in the wall of each cylinder adapted to be uncovered by the associated piston near the end of its power stroke, means for supplying motive fluid to said motors including two manuals, one for each motor and spaced to require two hand operation, and means actuated by each of said motors upon predetermined relative travel between its piston and cylinder for establishing communication between a motive fluid supply and the port in the cylinder wall of the other motor.

7. A pressing machine as in claim 5 and including an open exhaust port in each cylinder wall at the same end of the cylinder as the aforesaid port.

8. In a pressing machine, a pair of coacting relatively movable pressing members, two cylinder and piston motors and motion transmitting

mechanism connected therewith for relatively moving said members to completely close the press, the stroke of either of said motors alone being insufficient to completely close the press, 5 a port in the wall of each cylinder adapted to be uncovered by the associated piston near the end of its power stroke, means for supplying motive fluid to said motors including two manuals, one for each motor and spaced to require two hand operation, a valve casing associated with each motor and housing a normally closed inlet valve and a normally open outlet valve, a conduit establishing communication between said port in each motor cylinder wall and the inlet and outlet valves in the casing associated with the other motor, a supply of motive fluid for each valve casing, and means actuated by a movable part of each motor near the end of its power stroke for actuating the valves in its associated casing 10 to open the inlet and to close the outlet valve.

9. In a pressing machine, a frame, a stationary pressing member thereon, a coacting pressing member movable toward and from said stationary member, two axially aligned fluid motors each having cylinder and piston elements, one element of each motor being connected with the frame and the movable pressing member respectively, the other elements of said motors being rigidly connected together, the working strokes of both 15 motors being necessary to completely close the press, a port in the wall of each cylinder adapted to be uncovered by the associated piston near the end of its power stroke, means for supplying motive fluid to said motors including two manuals, one for each motor and spaced to require two hand operation, a valve casing associated with each motor and housing a normally closed inlet valve and a normally open outlet valve, a conduit establishing communication between said port in each motor cylinder wall and the inlet and outlet valves in the casing associated with the other motor, a supply of motive fluid for each valve casing, and means actuated by a movable part of each motor near the end of its power stroke for actuating the valves in its associated casing 20 to open the inlet and to close the outlet valve.

10. A pressing machine as in claim 8 and including a valve casing for each motor communicating with the working face of its piston, and a shuttle valve in the said casing adapted alternatively to establish communication with the manually controlled fluid supply for said motor or with the conduit communicating with the 25 port in said motor cylinder wall.

11. A pressing machine as in claim 8 and including a valve casing for each motor communicating with the working face of its piston, a shuttle valve in the said casing adapted alternatively to establish communication with the manually controlled fluid supply for said motor or with the conduit communicating with the 30 port in said motor cylinder wall, and means biasing said shuttle valve to establish communication 35 with the said conduit.

12. In a pressing machine, a frame, a stationary pressing member thereon, a coacting pressing member movable toward and from said stationary member, two axially aligned fluid motors each 35 having cylinder and piston elements, one element of each motor being connected with the frame and the movable pressing member respectively, the other elements of said motors being rigidly connected together, the working strokes of both 40 motors being necessary to completely close the

press, a port in the wall of each cylinder adapted to be uncovered by the associated piston near the end of its power stroke, means for supplying motive fluid to said motors including two manuals, one for each motor and spaced to require two hand operation, a valve casing rigidly mounted on each cylinder, each casing housing a normally closed inlet valve and a normally open outlet valve, a conduit establishing communication between said port in each motor cylinder wall and the inlet and outlet valves in the casing associated with the other motor, a supply of motive fluid for each valve casing, the inlet and outlet valves in each casing having a common actuator, and a cam on each piston rod adapted to operate the 45 actuator for its associated valves near the end of the power stroke of each motor.

13. A press as in claim 1 and including a third manual, a normally closed outlet valve operated thereby, a conduit connecting said valve with the 50 cylinder of one of said motors for exhausting the same, and means for opening the press.

14. A pressing machine as in claim 8, and including a valve casing for each motor communicating with the working face of its piston, a shuttle valve in the said casing adapted alternatively to establish communication with the manually controlled fluid supply for said motor or communication with an exhaust port, and means biasing said shuttle valve to establish communication with said exhaust port.

15. In a pressing machine, a pair of coacting relatively movable pressing members, two cylinder and piston motors and motion transmitting mechanism connected therewith for relatively moving said members to completely close the press, the stroke of either of said motors alone being insufficient to completely close the press, means for supplying motive fluid to said motors including two control members, one for each motor, and means actuated by each of said motors upon predetermined relative travel between its piston and cylinder for establishing a supply of motive fluid for the other of said motors independent of its control member.

16. In a pressing machine, a pair of coacting relatively movable pressing members, two cylinder and piston motors and motion transmitting mechanism connected therewith for relatively moving said members to completely close the press, the stroke of either of said motors alone being insufficient to completely close the press, means for supplying motive fluid to said motors including two control members, one for each motor, and means actuated by one of said motors upon predetermined relative travel between its piston and cylinder for establishing a supply of motive fluid for the other of said motors independent of its control member.

17. In a pressing machine, a pair of coacting relatively movable pressing members, two cylinder and piston motors and motion transmitting mechanism connected therewith for relatively moving said members to completely close the press, the stroke of either of said motors alone being insufficient to completely close the press, means for supplying motive fluid to said motors including two operator operated control members, one for each motor, and means actuated by each of said motors upon operation of said control members and upon predetermined relative travel between its piston and cylinder for establishing supply of motive fluid for the other of said motors independent of its control member.
